CLAIM

The ornamental design for a shoe sole, as shown and described.

DESCRIPTION

FIG. 1 is a bottom plan view of a shoe sole, showing my new design;

FIG. 2 is a right side elevational view, the showing of a shoe upper being for illustrative purposes only and forming no part of claimed design;

FIG. 3 is a left side elevational view thereof;

FIG. 4 is a front elevational view thereof; and,

FIG. 5 is a rear elevational view thereof.
